UNITED STATES PATENT OFFICE.

REVERDY R. WALLING, OF FREDERICK, MARYLAND.

SHUTTER-BOWER.

SPECIFICATION forming part of Letters Patent No. 445,210, dated January 27, 1891.

Application filed October 14, 1890. Serial No. 368,075. (No model.)

To all whom it may concern:

Be it known that I, REVERDY R. WALLING, a citizen of the United States, residing at Frederick, in the county of Frederick, State of Maryland, have invented certain new and useful Improvements in Shutter-Bowers, of which the following is a specification, reference being had therein to the accompanying drawings.

10 My invention relates to devices for securing window-blinds in any desired position; and the objects of my invention are to provide simple and inexpensive means for fastening a shutter so that it cannot be shaken loose by the wind, and in which the parts can be as operative when applied to a right-hand shutter as to a left-hand shutter, and thus permit a smaller stock of parts of the shutter-bowers to be kept by hardware stores.

15 Another object is to form a self-lock and permit shutters to be doubly locked without the addition of parts, and is an improvement upon Patent No. 420,180, granted to Zimmerman, January 28, 1890.

20 I attain these objects by the construction illustrated in the accompanying drawings, in which—

Figure 1 is a perspective view of a portion of the lower part of a window frame and shutter provided with devices to bow the latter and constructed in accordance with my invention. Fig. 2 is a horizontal section of the same. Fig. 3 is a transverse vertical section on line $z z$ of Fig. 2. Fig. 4 is a top view of a portion of the shutter-retaining rod of malleable cast metal before it is connected to the bracket-pin of the shutter.

In said drawings, A represents the sill of a window-frame, and B the shutter. To the inner face of the latter is secured a horizontally-slotted arm C, the base-plate C^2 of which is of such length as to extend upon a portion of the upright stile and also upon the bottom rail of the shutter, and as some of its retaining-screws are inserted into each of these parts it forms an iron connection therefor and gives strength to the shutter at one of its weak points. The top and bottom branches of the arm C are united together near their outer ends by a pin c , made either integral therewith or inserted in perforations made therein.

They are furthermore united on the outer side by a vertical plate or rib c^2 , formed integral therewith, and said rib assists in relieving the pivot-pin c of strain from the brace-rod D, as the loop d of the latter is adapted to bear against the rib when it loosely embraces the pin c .

55 The rod D is made, preferably, of malleable cast-iron, with the side d^2 of its loop open, as shown in Fig. 4, and after it is made to pass around the pin c it is pressed or closed against the body of the rod, as shown in Fig. 2. Said part of the body of the rod has a short bend to permit it to reach beyond the edge of the window-frame without touching it when the shutter is to be locked in an open position. The opposite end of the rod D is provided with a vertical cross-head D^2 , one part of which extends above said rod and the other below, so that the same casting C C^2 and rod D can be used in connection with either a right-hand or a left-hand shutter. The cross-head D^2 can also be used as a handle to lift the rod D.

70 To retain the shutter either in a closed and locked or in a partly-open position, a sill-plate E is screwed to the sill A. Said plate is in the form of a T and has in its body a series of round perforations e and a larger square hole e^2 in its head. The two branches of the sill-plate have their ends e^3 turned up, so that either one is adapted to enter into engagement with a pivoted catch F, secured to the shutter, and the outer face of the ends e^3 are beveled to permit the hooked lip f of the catch 85 to automatically ride up the beveled ends e^3 and drop into engagement therewith when the shutter is closed. The outer end or handle of the catch F has a D-shaped perforation F^2 therein to freely receive one of the standing parts of the cross-head of the rod D and be doubly locked by the latter. The inner end of the catch F has trunnions f^2 , serving as pivots therefor, that are received in the rearwardly-recessed cap-plate G. One of the 95 screws connecting said plate to the shutter is preferably inserted in its upright stile and the other in the bottom rail to give strength to the blind at that point. To give the desired strength to the body of the catch without materially increasing its weight, it is provided 100 with a rib f^3 on top thereof and the cap-plate

G has an open top at g to give free play to the catch and its rib. Upon the sill is also secured a small plate H, having a central cup or perforation to receive the cross-head of the rod D when it is desired to retain the shutter in an open position.

Having now fully described my invention, I claim—

1. In a shutter-bower, the combination of the horizontally-slotted arm C, having a base-plate and a side rib c^2 uniting the top and bottom portions of said slotted arm, the bent rod D, having a cross-head D^2 extending above and below said rod, and a sill-plate E, substantially as described.
2. The combination of the horizontally-slotted arm C, the bent rod D, having a cross-head D^2 extending above and below said rod, the pivoted catch F, having a perforated handle F^2 to receive one of the extensions of the

head D^2 , and a sill-plate having perforations therein and the two hooked ends e^3 , substantially as and for the purpose described.

3. The combination of the horizontally-slotted arm C, the bent rod D, having a cross-head D^2 extending above and below said rod, 25 the pivoted catch F, having a perforated handle F^2 to receive one of the extensions of the head D^2 , a rib f^3 on top thereof, and a cap-plate G, having an opening in its top for the passage of the catch and its top rib, and a T-shaped sill-plate having perforations therein and two hooked ends e^3 , substantially 30 as described.

In testimony whereof I affix my signature in presence of two witnesses.

REVERDY R. WALLING.
